ATION OF MAINE

ART OF CRACKING HYDROCARBONS

Application filed November 12, 1924. Serial No. 749,402.

This invention relates to improvements in cracking heavier hydrocarbon oils, such as gas oil, for the production of lighter hydrocarbon oils, such as gasoline or pressure distillate, by distillation under pressure. This application is in part a continuation of our copending application Serial No. 437,662, filed January 17, 1921, which has issued as Patent No. 1,547,993.

- 10 In cracking hydrocarbon oils by distillation under pressure, the oil is heated to a cracking temperature under pressure and the heavier oil, or a portion thereof, is broken down or "cracked" with the formation of 15 lighter oils which are vaporized and driven off. The cracking operation takes place gradually and progressively, part of the cracked constituents escaping as pressure distillate and part of the heavier cracked constituents remaining and mixing with the 20 charge of oil in the pressure still. A small amount of asphaltic, or pitch-like constituents, or heavy tar is also formed by the cracking operation. This tar remains in the 25 still and gradually accumulates due to the vaporization of cracked constituents and to the progressive formation of tar constituents. This tar accumulating in the oil in the still tends to deposit on the heating surfaces 30 of the still and in contact therewith tends to form a carbonaceous deposit thereon closely adhering thereto. Such carbonaceous materials and the heavy tar accumulating in the still charge are poor conductors 35 of heat and when deposited on the heating surfaces of the still which are externally exposed to heating gases interfere with heat transfer and insulate the wall from the protection afforded by the oil so 40 that the walls of the still are apt to become overheated the temperature of the metal of the heat transferring wall increasing over that of the oil to an extent dependent upon the thickness of the deposit and the 45 amount of heat externally delivered to the wall from the heating gases. As a consequence the pressure still must frequently be shut down for cleaning or the temperature of the heating gases must be reduced below that 50 which is most efficient. There is also con-

siderable danger involved due to possible bursting of the heat transferring walls at overheated points. The heating surfaces over which heating gases are first circulated are exposed to the highest temperature of the 55 heating gases and absorb the greatest amount of heat, and these surfaces are most apt to suffer. Heating surfaces immediately adjacent the furnace employed to heat the pressure still may also absorb a large amount of 60 heat by direct radiation from the furnace.

According to the present invention, the vapors from the cracking operation are subjected to a refluxing operation in direct contact with fresh oil and the reflux and admixed fresh oil are employed to protect the heating surfaces of the pressure still while at the same time the reflux and admixed fresh oil are subjected to advantageous cracking 65 conditions. All of the refluxed constituents 70 have been vaporized from the charge of oil in the still and are substantially free from tar constituents, and the fresh oil and admixed refluxed constituents, when admixed with the still charge, or a part thereof, assist 75 in reducing the concentration of tar constituents and in maintaining the concentration of tar constituents below saturation therein.

According to the present invention, the reflux and admixed fresh oil are first brought 80 into heat exchanging relation with the heating gases at their highest temperature before they are passed over other heating surfaces of the pressure still, and, as the light cracked constituents are vaporized and the 85 oil loses its content of crackable hydrocarbons and as the concentration of tar constituents increases, the oil is brought into heat exchanging relation with heating gases 90 which have been tempered and reduced in temperature by heat exchange with the reflux and admixed fresh oil by passing the oil of increased tar content over more remote heating surfaces of the pressure still. The heating gases while at highest temperature are 95 thus passed over heating surfaces which are in contact with oil relatively free of tar constituents, or in which the concentration of tar is least, and as the tar concentration increases the oil is passed over heating sur- 100

faces in contact with progressively tempered and cooler heating gases. The lighter crackable constituents of the reflux and admixed fresh oil are also subjected to advantageous cracking condition by heat exchange with the hottest heating gases. The heating surfaces of the pressure still most apt to suffer are thus protected by absorption of the heat transferred therethrough in heating and cracking the oil constituents of the reflux and admixed fresh oil and this heat available at high temperature is advantageously employed in a useful cracking operation rather than in the further cracking of tar constituents while a reduced concentration of tar constituents is maintained in the oil in contact with these initial heating surfaces preventing or materially reducing the formation of carbonaceous deposits thereon. The heat available in the heating gases, the temperature of which has been lowered by the heat absorbed in heating and cracking the reflux and admixed fresh oil, is then further employed to advantage in cracking the oil as tar constituents accumulate therein.

In carrying out the invention, the heating surfaces of the pressure still may be further protected and the heating of the pressure still charge equalized by providing progressively increased areas of heat transfer between the oil and the heating gases as the tar content of the oil increases and as the temperature of the heating gases decreases. The heating effect is thus equalized by increasing the area of heat transfer as the temperature of the heating gases decreases while an increased area of heating surface is provided in contact with the oil containing an increased tar content where deposition is most likely to occur. Additional fresh oil may also be passed over the initial heating surfaces together with the reflux and admixed fresh oil returned from the refluxing operation. The tar content of the pressure still charge may also be controlled and reduced by withdrawing tar from one or more portions of the still charge where the tar tends to accumulate.

The present invention is of special value and application in connection with cracking operations in which directed circulation of the still charge is maintained over the heating surfaces of the pressure still. Circulation may be maintained by convective action, or by mechanical forcing means such as a pump or pumps, or by the introduction of suitable gases. Circulation further assists in preventing or materially reducing the formation of carbonaceous deposits on the heating surfaces and assists in carrying tar constituents with the circulating oil. Circulation of the oil over the heating surfaces also promotes the heat transfer from the heating surface to the oil and further protects the heating surface in this way. Directed circula-

tion may be maintained either in the initial heating stages or in the later heating stages or in both.

The process of the invention may also with advantage be carried out in a series of stages or cycles, with circulation of the oil in each stage or cycle from a body of the oil in heat exchanging relation with the heating gases and back to the body, and transferring oil to successive stages as its tar content increases, circulating heating gases in heat exchanging relation with the oil in the stages or cycles successively in the order of increasing tar content, and returning reflux and admixed fresh oil from the refluxing operation to which the vapors from the cracking operation are subjected to the stage or cycle in which the oil is subjected to heat exchange with the heating gases of highest temperature.

In one aspect, the process of the present invention may be considered a process in which the reflux and admixed fresh oil are first subjected to a more or less intense cracking treatment and then, as tar and carbon accumulate in the oil, to a digestion treatment in which the cracking temperature is maintained by employing the heating gases from the initial cracking treatment.

While the invention is of particular advantage where the same stream of heating gases is employed for heating the oil in the successive stages of the process as the temperature of the heating gases is progressively reduced, certain advantages of the invention may be obtained by employing heating gases of separately regulated temperature in the successive stages, employing hotter heating gases for initially heating and cracking the reflux and admixed fresh oil and progressively cooler heating gases for heating the oil of progressively increasing tar content in the successive stages.

The process of the invention may be carried out in different types of apparatus. The reflux and admixed fresh oil may be returned through a tubular heater arranged to be heated by the heating gases as they first leave the furnace and arranged to discharge the oil into a shell or drum, or digestion chamber, for further treatment of the tar containing oil. The shell or digestion chamber may be arranged to be heated directly by the heating gases which have passed over the heater through which the reflux and admixed fresh oil is circulated, or the oil in the shell or digestion chamber may be heated by being circulated from and back to the shell or digestion chamber through a tubular heater arranged for heat exchange with the heating gases from the first heater. The successive heaters may also all be tubular in character, or a divided pressure still may be arranged to maintain a series of bodies of the oil in a series of compartments with a separate heater connected to each compartment with means

to return reflux and admixed fresh oil to the compartment connected to the heater over which the heating gases are first passed and to transfer oil successively through the compartments as the tar content of the oil increases.

The invention will be further described in connection with the accompanying drawings which illustrate in a diagrammatic way one form of apparatus adapted for carrying out the process of the invention. The apparatus illustrated is described and claimed in an application filed Jan. 17, 1921, Serial Number 437,662 and the process of the present invention is of special value and application in connection with pressure stills of this general character. The process of the invention may, however, be carried out in other and different apparatus.

In the accompanying drawings:

Fig. 1 represents a pressure still, in elevation and section with parts broken away, adapted for carrying out the process of the invention,

Fig. 2 is a section on line 2—2 of Fig. 1 with a condenser diagrammatically shown, and

Fig. 3 is a fragmentary section on line 3—3 of Fig. 1.

The pressure still illustrated comprises a drum 4 and a series of tubular heating elements communicating therewith arranged in the heating flue of a furnace 5. The heating flue comprises a series of connected vertical flues 6, 7, 8 and 9, the flue 6 also connecting with the furnace 5 and the flue 9 with a stack flue 10. The flues are arranged so that the heating gases from the furnace are passed successively therethrough to the stack.

A draft tube 11 is arranged for withdrawing waste heating gases from a point adjacent the exit of the heating flue 9 and returning them to the flue 6 for tempering the heating gases fresh from the furnace 5 in the flue 6.

The draft tube may be operated by a steam jet or other suitable forcing means. By returning waste heating gases in this way, the heating gases are tempered in the first heating flue, the volume and rate of circulation of the heating gases through the heating flues is increased, and the available heat in the recycled gases may be further utilized. By-passes 12 and 13 provided with regulating dampers 14 and 15 are provided for further controlling the distribution of heat in the several flues.

The still drum 4 is provided internally with a series of partitions 16, 17 and 18 dividing the drum into a series of compartments A, B, C and D and a corresponding series of heating elements separately communicating with each of these compartments are arranged in the heating flues. The heating element connected to compartment A is arranged in flue 6, that is the flue through

which the heating gases are first passed, the heating element of the next compartment B in the next flue 7, and so on, the heating element connected to the last compartment D being arranged in the last heating flue 9 through which the coolest heating gases are circulated. The partitions in the drum do not completely shut off the compartments from each other but extend a short distance above the normal liquid level therein leaving a common vapor space in the upper part of the drum. Overflow pipes 19, 20 and 21 are arranged for progressively transferring oil to successive compartments in the series, and these pipes are provided with bell caps 80 to prevent transfer of surface scum and froth to successive compartments.

Each of the heating elements connected to the respective compartments comprises these similar groups of heating tubes. Each of these groups comprises an outflow header 22, a series of upwardly inclined tubes 23 arranged through the heating flue for heat exchange with the heating gases therein, connecting headers 24, another series of upwardly inclined tubes 25 arranged through the heating flue, and an inflow header 26. In order to facilitate cleaning and repair the headers are arranged outside of the heating flues and are formed with plugged hand holes 95 in alignment with the heating tubes. In order to equalize the heating effect in the several heaters and to provide an increased area of heat transfer as the tar content of the oil increases, as will presently appear in more detail, the heat transferring area of the several heaters is progressively increased as the temperature of the heating gases declines. In the apparatus illustrated, the heater connected to the first compartment A has four tubes in each group, that connected to compartment B eight tubes, that connected to compartment C twelve tubes and that connected to the last compartment D sixteen tubes.

Arranged above the drum 4 is a reflux tower 27 adapted to receive vapors from the vapor space of the drum 4 and to discharge reflux and admixed oil into the first compartment A connected to the heating element arranged in heat exchanging relation with the hottest heating gases. A connection 28 is provided for introducing fresh oil into the upper part of the reflux tower over the baffles therein and in direct contact with the vapors therein. A connection 29 discharging into the first compartment A is provided for the introduction of supplementary or additional fresh oil. The vapors escape from the reflux tower through vapor line 30 to a condenser diagrammatically illustrated at 31. The pressure in the still may be reduced and controlled by a regulating valve 32 arranged between the reflux tower and the condenser or by a valve 33 arranged beyond the con-

denser. In order to provide for drainage, and for withdrawal of tar during the cracking operation the lower ends of the inflow headers in each heating element are connected to a manifold 34 having a valved outlet 35, the outlet from the last compartment D being designated 35'.

The reflux tower and the still drum may, with advantage, be covered or protected 10 with suitable heat insulation, such as an asbestos or mineral wool jacket.

In carrying out the process of the invention in the apparatus illustrated, the still is initially charged with oil, through connection 29 the oil successively overflowing into the adjacent compartments as the preceding compartments are filled, and brought to the cracking temperature and pressure in the usual way. The pressure employed may 20 differ with different charging stocks and for the production of different pressure distillates. With gas oil character charging stocks for the production of gasoline character distillates, pressures in the neighborhood of 90 25 to 125 pounds per square inch or more may be employed. In cracking a kerosene character charging stock to produce a gasoline character distillate, considerably higher pressures may be used, for example, pressures up 30 to 300 pounds per square inch or more may be employed.

After the still charge is brought to the cracking temperature and pressure, the cracked vapors rise from the several compartments and pass upwardly through the reflux tower 27, and the introduction of fresh oil through connection 28 is begun. In the reflux tower the fresh oil is intimately contacted with the vapors from the still, refluxing 40 the heavier vapors and preheating the fresh oil, and the reflux and admixed fresh oil are returned to compartment A. As the reflux and admixed fresh oil are introduced into compartment A, oil from this first compartment which has been deprived of a part 45 of its crackable constituents and contains some tar constituents overflows into the second compartment B where it is further cracked and a further part of its components are 50 vaporized. In the same way oil is transferred from compartment B to compartment C and from compartment C to compartment D as the cracked constituents are vaporized and as the tar accumulates, the oil in the 55 successive compartments containing less and less of the original oil constituents and more and more heavy tarry constituents.

Tar may also be withdrawn from one or more of the successive compartments, and 60 with particular advantage from the last compartment D through connection 35'. The introduction of fresh oil into the reflux tower is controlled to regulate the refluxing operation. Where no tar, or only a relatively 65 small amount of tar is withdrawn, the

amount of fresh oil introduced into the reflux tower may correspond approximately to the amount of distillate taken off or may be somewhat in excess of this amount. Where larger amounts of tar are withdrawn, the 70 still charge is maintained by the introduction of an increased amount of fresh oil, and the fresh oil supplied may be divided and introduced partly into the reflux tower and partly into compartment A directly.

The heating gases from the furnace 5 are passed successively over the heating elements connected to compartments A, B, C and D in order, so that the oil in the first compartment A, including the reflux and admixed fresh oil, is subjected to the highest temperature, that in the second compartment B to a somewhat lower temperature, and so on. The heat absorbed by the oil in the first compartment A is employed to crack the oil constituents of the reflux and admixed fresh oil and this oil is circulated over the heating surfaces protecting them against the highest temperature of the heating gases, and as the tar content of the oil increases it is transferred 80 to successive compartments where it is subjected to heat exchange with heating gases of progressively lower temperature. At the same time the heating effect in the successive compartments is equalized by the progressively increased area of heat transfer provided, and the difficulties and dangers incident to the formation of carbonaceous deposits are materially reduced due both to the decreased temperature of the heating gases and the increased area of heat transfer and consequent reduction in the rate of heat transfer per unit of area. In all of the heating elements the absorption of heat by the circulating oil protects the heating surfaces, particularly in the first where the heating element is exposed to the hottest heating gases and where the circulating oil contains the reflux and admixed fresh oil and the 90 least content of tar.

It will thus be seen that the present invention provides an improved method of cracking hydrocarbon oils by distillation under pressure in externally heated pressure stills in which fresh oil is supplied to the cracking operation and in which the fresh oil is first employed to promote and control a refluxing operation to which the vapors from the pressure still are subjected and then, in admixture with the reflux, to protect the heating surfaces of the pressure still subjected to heat exchange with the hottest heating gases while the lighter crackable constituents are subjected to particularly advantageous cracking conditions. One of the important advantages of the present invention is that it enables the cracking operation to be carried out over a prolonged period without, however, decreasing the rate of cracking by reducing the temperature of 100 105 110 115 120 125 130

the heating gases or otherwise. Another important advantage of the invention is that it enables an improved application of the heating gases to the cracking operation so that both the efficiency and the capacity of the pressure still may be increased.

We claim:

1. An improved method of cracking hydrocarbon oils, which comprises heating the oil to a cracking temperature under pressure in a series of stages and circulating the oil to successive stages as the tar content of the oil increases, circulating heating gases in heat exchanging relation successively with the oil in the stages in the order in which the oil is circulated therethrough, maintaining progressively increasing areas of heat transfer between the heating gases and the oil in the successive stages in the same order, subjecting the vapors from the cracking operation to a refluxing operation in direct contact with fresh oil, and returning the reflux and admixed fresh oil to the first stage in which the tar concentration is least.

2. A process for cracking hydrocarbons comprising passing the oil through a heating coil wherein it is raised to a conversion temperature, discharging the heated oil into an enlarged conversion chamber, taking off vapors from said conversion chamber for dephlegmation and condensation, circulating unvaporized oil from said conversion chamber through a cooler portion of the heating coil zone than that in which said heating coil is positioned and back to said conversion chamber.

3. A process of cracking hydrocarbon oil, consisting in passing the oil through a heating coil wherein it is subjected to a conversion temperature, in discharging the heated oil into an enlarged conversion chamber, in passing the vapors issuing from said conversion chamber to a dephlegmator, in returning reflux condensate from the dephlegmator to said heating coil, in condensing the vapors issuing from the dephlegmator and in collecting the resulting distillate, in circulating the unvaporized oil from said conversion chamber through an independent heating element wherein it is subjected to a lower temperature than the oil in said coil and back to the conversion chamber, and in maintaining a superatmospheric pressure on the oil undergoing conversion.

4. A process for cracking hydrocarbons comprising passing the oil through a heating coil wherein it is raised to a conversion temperature, discharging the heated oil into an enlarged conversion chamber, taking off vapors from said conversion chamber and refluxing the vapors in heat exchanging relation with fresh oil, circulating unvaporized oil from said conversion chamber through

a cooler portion of the heating zone than that in which said heating coil is positioned and back to the conversion chamber, and supplying the fresh oil from the refluxing zone to the heating coil.

5. A process of cracking hydrocarbon oil consisting in passing the oil through a heating coil wherein it is subjected to a conversion temperature, in discharging the heated oil into an enlarged conversion chamber, in passing the vapors issuing from said conversion chamber to a dephlegmator, in introducing fresh oil to the dephlegmator in direct contact with the vapors therein, in returning reflux condensate and admixed fresh oil from the dephlegmator to said heating coil, in condensing the vapors issuing from the dephlegmator and in collecting the resulting distillate, in circulating the unvaporized oil from said conversion chamber through an independent heating element wherein it is subjected to a lower temperature than the oil in said coil and back to the conversion chamber, and in maintaining a superatmospheric pressure on the oil undergoing conversion.

6. An improved method of cracking hydrocarbon oils, which comprises circulating the oil in each of a series of cycles from a body of the oil in heat exchanging relation with heating gases and back to the body, transferring the oil to successive cycles as the tar content of the oil increases, heating the oil to a cracking temperature under pressure by circulating heating gases in heat exchanging relation successively with the oil in the cycles in the order of increasing tar content, maintaining progressively increasing areas of heat transfer between the heating gases and the oil in the successive cycles in the same order, subjecting the vapors from the cracking operation to a refluxing operation, and returning the reflux to the first cycle in which the tar concentration is least.

7. A process of cracking hydrocarbon oil, consisting in passing the oil through a heating coil wherein it is subjected to a conversion temperature, in discharging the heated oil into an enlarged conversion chamber, in passing the vapors issuing from said conversion chamber to a dephlegmator, in returning reflux condensate from the dephlegmator to said heating coil, in condensing the vapors issuing from the dephlegmator and in collecting the resulting distillate, in circulating the unvaporized oil from said conversion chamber through an independent heating element wherein it is subjected to a lower temperature than the oil in said coil and back to the conversion chamber, in preventing the return of unvaporized oil which has passed through said independent heating element to said heating coil, and in maintaining a superatmospheric pressure on the oil undergoing conversion.

8. A process of cracking hydrocarbon oil,

- consisting in passing the oil through a heating coil wherein it is subjected to a conversion temperature, in discharging the heated oil into an enlarged conversion chamber, in passing the vapors issuing from said conversion chamber to a dephlegmator, in returning reflux condensate from the dephlegmator together with additional fresh oil to said heating coil, in condensing the vapors 5 issuing from the dephlegmator and in collecting the resulting distillate, in circulating the unvaporized oil from said conversion chamber through an independent heating element wherein it is subjected to a lower temperature than the oil in said coil and back 10 to the conversion chamber, in preventing the return of unvaporized oil which has passed through said independent heating element to said heating coil, and in maintaining a super- 15 atmospheric pressure on the oil undergoing conversion.
